LOCK

Charles Ledin, Stamford, Conn., assignor to The
Yale & Towne Manufacturing Company, Stam-
ford, Conn., a corporation of Connecticut

Application March 31, 1936, Serial No. 71,856

12 Claims. (Cl. 70—151)

This invention relates to a lock of the rim type in which a considerable portion of the lock is adapted to be housed in an open mortised portion of the door.

Those skilled in the art will readily appreciate that rim locks are usually housed in a casing maintained entirely on the outside face of one side of a door and operable either by a knob extending from the casing, or by a cylinder located on the other side of the door and having a tongue or connecting bar extending into the lock casing.

Such rim locks are usually quite unsightly but have an advantage in that they are relatively simple to install. My invention relates to a lock similar to the type just described, but in which about half the casing is adapted to be maintained within an open mortised portion or recess in the door, so that only a small part of the casing projects beyond the face of the door. This gives a very pleasing effect, and because of my particular construction, which will be described later on, I am able to obtain this effect without complicating the method of applying the lock to a door.

Before describing in detail the features of my invention, it may be well to indicate generally its construction and method of operation. The lock comprises a base plate which is in effect a lock casing adapted to occupy a recess or open mortised portion of the door. This base plate, or lower casing as it may also be termed, has a series of lugs which rest on the surface of the door surrounding the recess, and which limit the insertion of the base plate into the recess or open mortised portion. Preferably, screws are adapted to enter the bottom surface of the base plate to secure the same to the bottom surface of the open mortised portion, and the degree of movement of the base plate into the open mortised portion under the influence of these screws is, of course, determined by the lugs resting against the face of the door.

The outer casing portion of my lock is formed decoratively, and it holds in position the bolt and a cam for retracting the bolt. The bolt and cam are mounted on this casing portion, but extend beyond it so as to lie partially, at least, in the open mortised portion of the door. This outer casing has a peripheral edge portion adapted to lie just outside the open mortised portion of the door or recess, so as to entirely hide that recess and to give a very pleasing effect. The outer casing is preferably equipped at its rear end with a lug adapted to interlock with

an upstanding ear on the base plate at the rear of the base plate. At its front end, the casing has an end surface adapted to lie in the plane of the end face of the door and arranged to be secured by screws, preferably, to upstanding ears at the front end of the base plate.

The construction of the lug at the rear of the outer casing, and the perforated ear on the base plate, is such that when the screws at the front end are tightened, cooperating cam surfaces on the lugs and the perforated ear of the base plate will cause the casing and base plate to draw together laterally as well as endwise, to move the casing tightly against the surface of the door, and thus give a very pleasing appearance to the lock.

My invention comprises further details which are of course important, but which will be described in detail hereinafter in connection with the drawings, wherein a preferred embodiment of my invention is shown.

In the drawings, Fig. 1 is a view of the outer casing of my lock and the strike cooperable therewith. Fig. 2 is a section through the lock and strike, showing the construction of the parts. Fig. 3 is a view substantially along section lines 3—3 of Fig. 2. Fig. 4 is an end view of Fig. 3, looking at it from the left. Figs. 5, 6 and 7 are different views of the construction of the bolt and the bolt retracting means, and the outer casing portion.

Referring now more particularly to the drawings, it will be noted that there is a door 10 having an open mortised portion, or recess 11, in which is adapted to lie the base plate or lower casing portion 12. This base plate 12 has an upstanding ear 13, which is perforated at 14 for a purpose which will be explained presently. The base plate has also a series of upstanding lugs 15 bent over at 16 and cooperable with the edge of the door 10 surrounding the recess or open mortised portion 11. A pair of screws 17 traverse perforated portions of the base plate, as is best seen in Figs. 2 and 3, and thus secure the base plate in the recess at a depth determined by the portions 16. The base plate 12 is further secured relatively to the recess 11 by screws 18 lying between the base plate and lugs 19 formed on a cylinder lock 20, which cylinder lock is adapted to operate the locking mechanism through a connecting bar 21 in a manner well understood in the art. The method of securing the base plate in the recess may be modified readily, the main feature of the construction

being the means determining the position of the base plate relatively to the face of the door.

The outer casing is designated by reference numeral 22 and has mounted thereon a bolt retracting knob 23 having fixed thereto a cam 24 bearing pin 25 which acts to retract the bolt, as will be explained later, when the knob 23 is rotated.

The outer casing has a peripheral edge portion 26 adapted to lie just outside the recess 11 and to fit against the face of the door surrounding the recess, as is best seen from Figs. 2 and 3. A lug 27 extends from the casing at its inner end and is adapted to rest within the perforation 14 of the upstanding ear 13 of the base plate for interlocking with the base plate, as will be readily understood.

At the front end of the outer casing, there is formed an end surface 28 perforated at 29 for a pair of screws 30 which are adapted to enter threaded upstanding ears 31 in the base plate 12. It will be readily appreciated that when the screws 30 are rotated to their extreme position, they act to draw the base plate and casing together endwise. Because the lug 27 has a cam surface 27a cooperable with the perforation 14 of ear 13, the relative endwise movement of the casing and plate caused by the turning of the screws 30 acts to cam the outer casing and base plate together, and to force the peripheral edge 26 of the outer casing firmly against the face of the door or to any slight preferred spacing away from the door. All this adjustment and securing of the outer casing is, of course, controlled by the securing screws for the base plate, and the locating lugs 16 of the said base plate.

The outer casing 22 carries the bolt of my lock, designated by reference numeral 35. The bolt has an integral tail portion 36 and a central spring 40 supporting rod-like portion 37, on which is mounted a spring 38 maintained between the rear surface 39 of the bolt and a washer 40 backed up by a perforated upstanding lug 41 through which the portion 37 traverses when the bolt is retracted, while the spring is compressed against the washer 40. The cam 24 of knob 23, through the pin 25 previously described, is adapted to retract the bolt by cooperation with surfaces 42 and 43 of the tail portion 36 of the bolt. The bolt is reversible for right and left hand doors, and, therefore, is made symmetrical with one of the surfaces 42, 43 available to the pin 25 regardless of the particular hand of the lock assembly.

While normally the pin 25 is adapted to rest against the portion 42 of the tail of the bolt in the assembly illustrated, it is possible to rotate the cam from the position of Fig. 5 to the position of Fig. 6 so as to permit the bolt to be thrown an extra amount by the spring, as is easily seen by reference to Figs. 5 and 6. In the position of Fig. 6 also, the bolt 35 is deadlocked because of the position of the pin 25 opposite the surface 44 of the latch bolt tail, the pin 25 being in a dead center position so as to obstruct rearward movement of the bolt 35.

For maintaining the bolt 35 in a retracted position, best illustrated in Fig. 7, I use a thumb piece 45, shown in Figs. 1 and 2, maintained for sliding movement relatively to a slot 46 of the casing 22. Secured to the member 45 is a slide piece 47 having a spring portion 48 cooperable with a lip 49 on the casing to maintain the slide piece 47 in its position of Fig. 6, or in its position of Fig. 7.

In its position of Fig. 7, the slide piece 47 is so located that the right hand end of an angular lug 50 thereon cooperates with a lug 51 on the upper side of the bolt for maintaining the bolt against outward movement so that the bolt is retained in its position of Fig. 7. The angular position of the lug 50 is adapted to prevent the lug and the member 47 from obstructing the rearward movement of the bolt from the position of Fig. 6 to the position of Fig. 7, since the angular surface will permit the member 47 to be cammed upwardly by the rear of the lug 51. As was already indicated, the bolt 35 is made symmetrical so that it is reversible and thus has two lugs 51 in addition to the two portions 42 and 43 on the bolt tail already described.

I provide stop lugs 35a on the outer casing portion 22 which limit the retractive movement of the bolt 35. I also provide a struck-up lug 24a on the cam 24 cooperable with a lug 22a for limiting the rotation of the cam 22. For cooperation with the bolt 35, I utilize a strike 52 shown only in Fig. 2, this strike being of the usual form well known in the art, except that it is designed for particular cooperation with the locking mechanism of the main portion of my lock.

For operating the cam pin 25 from the outside of the door, as I have already indicated, I provide a cylinder lock 20 equipped with a connecting bar 21 which may be rotated in a manner well understood in the art. A cam 53 is mounted for rotation on the plate 12 and is perforated at 54 for the entry of the connecting bar 21. The cam 53 also carries a pair of arms 55 which cooperate with the pin 25, as best illustrated in Fig. 2. It is easily seen that rotation of the connecting bar 21 by the cylinder lock 20 will retract the bolt through coaction of one of the arms 55 with the pin 25. I believe that the operation of my invention will now be quite clear to those skilled in the art.

I now claim:

1. In a lock of the class described, a base plate having a depressed portion adapted to occupy an open mortised portion in a door and having also offset portions adapted to overlie the surface of the door about said open mortised portion, fastening screws securing said base plate to said door, a casing having a peripheral outlining portion adapted to lie with its edge juxtaposed relatively to the surface of the door about the edge of said open mortised portion while covering said portion, lock mechanism carried by said casing and fitting into the depressed portion of said base plate lying in the open mortised portion of the door, and screws for joining said casing to the said base plate and thereby assembling the lock on said door.

2. In a lock of the class described, a base plate having a depressed portion adapted to occupy an open mortised portion in a door and having also offset portions adapted to overlie the surface of the door about said open mortised portion, fastening screws securing said plate to the door, screw threaded lugs at one end of said base plate and upstanding therefrom, a perforated ear at the other end of said base plate and upstanding therefrom, a casing having a peripheral outlining portion adapted to lie with its edge against the surface of the door about the edge of said open mortised portion while covering said portion, lock mechanism carried by said casing and fitting into the depressed portion of said base plate lying in the open mortised portion of the door, an outer end surface of said casing adapted to be aligned

with the edge of the door, a hook formed near the inner end of said casing and on the inside surface thereof and extending beyond the peripheral outlining portion thereof, said hook being adapted 5 for engagement with the perforated lug of said base plate, and screws for joining the outer end surface of said casing with the screw threaded lugs on said base plate.

3. In a lock of the class described, a base plate 10 adapted to occupy an open mortised portion in a door, offset shoulders on said base plate overlying the surface of the door about the edge of said open mortised portion and determining the depth of insertion of the base plate into said open 15 mortised portion, fastening screws securing said base plate to the bottom surface of said open mortised portion, screw threaded lugs at one end of said base plate and upstanding therefrom, a casing having a peripheral outlining portion 20 adapted to lie with its edge against the surface of the door about the edge of said open mortised portion while covering said portion, an outer end surface of said casing adapted to be aligned with the edge of the door, and screws for joining the 25 outer end surface of said casing with the screw threaded lugs on said base plate.

4. In a lock of the class described, a base plate 30 adapted to occupy an open mortised portion in a door, offset portions on said base plate overlying the surface of the door about the edge of said open mortised portion and limiting the depth of insertion of the base plate into said open 35 mortised portion, fastening screws securing said base plate relatively to the bottom surface of said open mortised portion, screw threaded lugs at one end of said base plate and upstanding therefrom, a perforated ear at the other end of said base plate and upstanding therefrom, a casing having a peripheral outlining portion adapted 40 to lie with its edge against the surface of the door about the edge of said open mortised portion while covering said portion, an outer end surface of said casing adapted to be aligned with the edge of the door, a hook formed near the inner 45 end of said casing and on the inside surface thereof and extending beyond the peripheral outlining portion thereof, said hook being adapted for engagement with the perforated lug of said base plate, and screws for joining the outer end 50 surface of said casing with the screw threaded lugs on said base plate.

5. In a lock of the class described, a base plate 55 adapted to occupy an open mortised portion in a door, offset shoulders on said base plate overlying the surface of the door about the edge of said open mortised portion and limiting the depth of insertion of the base plate into said open 60 mortised portion, fastening screws securing said base plate relatively to the bottom surface of said open mortised portion, screw threaded lugs at one end of said base plate and upstanding therefrom, a perforated ear at the other end of said base plate and upstanding therefrom, a casing having a peripheral outlining portion adapted 65 to lie with its edge against the surface of the door about the edge of said open mortised portion while covering said portion, an outer end surface of said casing adapted to be aligned with the edge of the door, a hook formed near the inner end of said 70 casing and on the inside surface thereof and extending beyond the peripheral outlining portion thereof, said hook having a cam surface for engagement with the perforated lug of said base plate, and screws for joining the outer end surface 75 of said casing with the lugs on said base plate for

drawing said casing endwise relatively to said plate whereby through the cam surface on the hook to draw said plate and casing together laterally as well as endwise.

6. In a lock of the class described, a base plate 5 adapted to occupy an open mortised portion in a door, offset shoulders on said base plate overlying the surface of the door about the edge of said open mortised portion and limiting the depth of insertion of the base plate into said open 10 mortised portion, fastening screws securing said base plate relatively to the bottom surface of said open mortised portion, an open casing having a peripheral outlining portion adapted to lie with its edge against the surface of the door about 15 the edge of said open mortised portion while covering said portion, an outer end surface of said casing adapted to be aligned with the edge of the door, screws for joining the outer end surface of said casing with said base plate, a bolt retracting cam on said base plate, a cylinder lock secured to said base plate, and a tongue on said cylinder lock engaging said cam.

7. In a lock of the class described, a base plate 20 adapted to occupy an open mortised portion in a door, offset shoulders on said base plate overlying the surface of the door about the edge of said open mortised portion and limiting the depth of insertion of the base plate into said open 25 mortised portion, fastening screws securing said base plate relatively to said open mortised portion, a casing having a peripheral outlining portion adapted to lie with its edge against the surface of the door about the edge of said open 30 mortised portion while covering said portion, an outer end surface of said casing adapted to be aligned with the edge of the door, screws for joining the outer end surface of said casing with the said base plate, a bolt retracting cam on said base plate, a bolt and bolt retracting mechanism carried by said casing, said bolt retracting mechanism being operable by said base plate cam when said casing is joined to said base plate.

8. In a lock of the class described, a base plate 35 adapted to occupy an open mortised portion in a door, offset shoulders on said base plate overlying the surface of the door about the edge of said open mortised portion and limiting the depth of insertion of said base plate into said open 40 mortised portion, fastening screws securing said base plate relatively to said open mortised portion, screw threaded lugs at one end of said base plate, a casing having a peripheral outlining portion adapted to lie with its edge against the surface of the door about the edge of said open mortised portion while covering said portion, an outer end 45 surface of said casing adapted to be aligned with the edge of the door, screws for joining the outer end surface of said casing to the lugs on said base plate, a bolt retracting cam on said base plate, a bolt and bolt retracting mechanism carried by said casing and extending therefrom beyond the plane of the edge of its peripheral outlining portion and therefore into said open mortised portion of the door, said bolt retracting mechanism being operable by said base plate cam when said casing is joined to said base plate.

9. In a lock of the class described, a base plate 50 adapted to occupy an open mortised portion in a door, offset shoulders on said base plate overlying the surface of the door about the edge of said open mortised portion and limiting the depth of insertion of the base plate into said open 55 mortised portion, fastening screws securing said base plate to said open mortised portion, screw thread- 75

ed lugs at one end of said base plate, a perforated ear at the other end of said base plate and upstanding therefrom, a casing having a peripheral outlining portion adapted to lie with its edge 5 against the surface of the door about the edge of said open mortised portion while covering said portion, an outer end surface of said casing adapted to be aligned with the edge of the door, and a hook formed near the inner end of said casing 10 and on the inside surface thereof and extending beyond the peripheral outlining portion thereof, said hook having a cam surface for engagement with the perforated lug of said base plate, and screws for joining the outer end surface of said 15 casing with the lugs on said base plate for drawing said casing endwise relatively to said plate whereby through the cam surface on the hook to draw said plate and casing together laterally as well as endwise.

20 10. In a lock of the class described, a base plate adapted to occupy an open mortised portion in a door, offset shoulders on said base plate overlying the surface of the door about the edge of said open mortised portion and limiting the depth of 25 insertion of the base plate into said open mortised portion, fastening screws securing one end of said base plate relatively to said open mortised portion, a lock cylinder against the surface of the door opposite said base plate, screws between said 30 cylinder and base plate for securing the other end of said base plate relatively to said cylinder and therefore to said open mortised portion, screw threaded lugs at one end of said base plate and upstanding therefrom, a casing having a peripheral outlining portion adapted to lie with its

edge against the surface of the door about the edge of said open mortised portion while covering said portion, an outer end surface of said casing adapted to be aligned with the edge of the door, and screws for joining the outer end surface of 5 said casing with the lugs on said base plate.

11. In a lock of the class described, a base plate having a depressed portion adapted to occupy an open mortised portion in a door, and having also offset portions adapted to overlie the surface of 10 the door about said open mortised portion, fastening screws securing said base plate to said door, a casing having a peripheral outlining portion adapted to lie with its edge juxtaposed relatively to the surface of the door about the edge 15 of said open mortised portion while covering said portion, lock mechanism carried by said casing and fitting into the depressed portion of said base plate lying in the open mortised portion of the door, and screws for joining said casing to the 20 said base plate.

12. In a lock of the class described, a base plate having a depressed portion adapted to occupy an open mortised portion in a door, and having also offset portions adapted to overlie the surface of 25 the door about said open mortised portion, fastening screws securing said base plate to said door, a casing having a peripheral outlining portion adapted to lie with its edge juxtaposed relatively to the surface of the door about the edge 30 of said open mortised portion while covering said portion, and screws for joining said casing to the said base plate.

CHARLES LEDIN.
